UNITED STATES PATENT OFFICE.

CHARLES H. ANDERSON, OF LEXINGTON, KENTUCKY.

CARBURETER.

1,362,664.

Specification of Letters Patent. Patented Dec. 21, 1920.

Application filed January 17, 1919. Serial No. 271,648.

To all whom it may concern:

Be it known that I, CHARLES H. ANDERSON, a citizen of the United States, and a resident of Lexington, in the county of Fayette and State of Kentucky, have invented certain new and useful Improvements in Carbureters for Gasolene-Engines; and I do hereby declare the following to be a full, clear, and exact description of the invention, such as will enable others skilled in the art to which it appertains to make and use the same.

My invention relates to an improvement in carbureters for gasolene engines, one object being to provide improved means for opening the needle valve by the suction of the engine and for holding it open while the engine is running, the extent of opening movement of the said needle valve being controlled by the movement of the throttle valve in the suction pipe.

A further object is to provide means for independently adjusting the needle valve with relation to the throttle valve.

A further object is to provide means whereby after the throttle and the needle valve have been adjusted for relative movement, the needle valve controlling means may be re-adjusted without disturbing the throttle valve.

A further object is to provide means for yieldingly holding the needle valve in its seat when the engine is not running.

With these and other objects in view my invention consists in the parts and combination of parts as will be more fully explained and pointed out in the claims.

In the accompanying drawings Figure 1 is a view in side elevation of my improvement; Fig. 2 is a view in vertical longitudinal section of the same; Fig. 3 is a view in horizontal section on the line $\alpha\alpha$ of Fig. 1 and Fig. 4 is a view in elevation of the needle valve and its actuating mechanism, one half of the casing being shown in section.

1 represents the suction tube of a carbureter having a flanged end 2 for its attachment to the intake manifold of an internal combustion engine. The throttle valve 3 is secured to a shaft 4 mounted adjacent the intake end of the tube 1 and is provided at one end with the crank 5 connected by pitman 6 with the crank 7 on shaft 8. This shaft is mounted eccentrically in the cylindrical bushing 9, and is adapted to be turned

or partly rotated therein, and the bushing 9 is mounted to turn in the bearing 10 formed in or attached to the cap 11, the latter being secured to the outer end of the cylinder 12. 60 The bushing or barrel 9 is provided at its outer end, outside of cap 11, with the crank 13 which is connected by rod 14 with mechanism on the dash or within reach of the driver whereby the said barrel or bushing 9 65 may be turned or adjusted while the engine is running.

Secured to the inner end of shaft 8 within the cap 11, is the arm 15 carrying a roller 16 which rests within a slot in the head 17 of 70 the piston 18. The slot in which the roller 16 rests extends crosswise the head and is of a size sufficient to receive the roller 16 without any lost motion between the parts. The upper end of the head is in the form of a 75 cylindrical rod 19 which is supported for vertical movement in the bearing 20 at the upper end of cap 11. The piston 18 is integral with or secured to the head 17 and has a close fit in cylinder 12 which is preferably cast integral with the suction tube 1 of the carbureter.

Piston 18^a is also located in the cylinder 12 below piston 18 and is rigidly secured to the upper end of the needle valve 21, which 80 is provided with a shoulder 22 for cutting off the supply of gasolene, and with a tapering end 23 for regulating the supply, the said tapering end being constructed to feed the proper proportion of gasolene to make 90 the proper mixture with the air admitted around the throttle valve. When the throttle valve is closed, the needle valve should be seated on its shoulder 22, and as the throttle is opened the needle valve will be 95 lifted as explained below to permit of the passage of gasolene, in amounts varying with the extent of the opening around the throttle.

Pistons 18 and 18^a are located in the cylinder 12, and a port 24 connects the suction tube 1 of the carbureter with cylinder 12 between the two pistons so that when the engine is working the suction from the latter tends to pull the pistons 18 and 18^a 105 toward each other, but as piston 18 is held against such movement by the crank arm 15 to which it is connected, piston 18^a will move upwardly toward piston 18 and carry with it the needle valve 21, thus permitting 110 the gasolene to flow from the spray nozzle 25 coupled up to a gasolene supply tank, the

extent of said upward movement of the piston 18^a and the needle valve being governed by the position of the pin 26 carried by the upper piston 18.

5 Cylinder 12 is provided with a port 12^a opening into the outer air from a point below the needle carrying piston so as to provide for the free entrance and escape of air from the underside of the latter.

10 Mounted in the hub of the upper piston 18 is the stop pin 26 having a head which is in line with the hub of piston 18^a or with the end of the needle valve in said hub. This pin has a vertical movement in the piston 15 18 and terminates at its upper end in a slot 27 formed in the head 17 of piston 18, and is sustained in such position by the pin holding device 28 passing through the upper end of the stop pin and normally resting on 20 the floor of said slot 27. The slot 27 is of a length sufficient to permit of longitudinal movement of the stop pin 26, so that normally the said pin is free to give and move upwardly with the lower piston 18^a until 25 stopped by its head engaging the hub of the upper piston and is only held down and in contact with the lower piston when the needle valve is closed and there is no suction through the carburetor as will be explained later on.

This stop pin acts as a stop for the lower piston and its position relative to the latter is regulated and controlled by the upper piston.

30 With the throttle valve 3 and upper piston 18 connected as previously explained, it follows that when the throttle valve is operated to admit air, the upper piston will be elevated, the extent of upward movement of 35 the latter being controlled by the extent of opening movement of the throttle. If now the engine be cranked or otherwise started, the suction through the suction tube 1 of the carburetor creates a suction in port 24 40 and the cylinder 12, which is in communication with said port and produces a vacuum in the cylinder which tends to pull the pistons toward each other. As the upper piston is connected with the lever and crank 45 mechanism previously explained, and hence 50 is only movable when said parts are actuated for opening or closing the throttle valve, it follows that when the vacuum is created in the cylinder, the upper piston remains stationary and the lower one moves up carrying 55 with it the needle valve 21, the extent of upward or opening movement of said needle valve being dependent on the extent of the opening around the throttle valve. As the 60 lower piston moves up it engages the head of the stop pin 26 and elevates the latter until the head of the pin contacts with the end of the hub of the upper piston where it remains immovable as long as the suction is 65 continued through the suction tube 1. When

the throttle valve 3 is closed, or suction discontinued through the suction tube 1, the vacuum in the cylinder 12 is destroyed thus permitting the lower piston 18^a to drop to its lowermost position, and seat the closing 70 shoulder 22 of the needle valve onto its seat on the spray nozzle.

The means for holding the needle valve down onto its seat when the throttle valve is closed, comprises the lever 29 mounted on 75 a bracket 30 fixed to or integral with the head 17 of the piston 18. One end of the lever rests within slot 27 in the head 17, immediately over the upper end of stop pin 26, while the opposite end of said lever rests 80 in the plane of the upper end of the upwardly pressed spring plunger 31. As the throttle valve is turned to its closed position, the upper piston 18 and its head 17, are through the parts 5—6—7 and 8, moved 85 downwardly to their lowermost positions, and this downward movement of the head 17 carries one end of lever 29 into contact with the upper end of plunger 31. This contact first causes lever 29 to turn on its fulcrum 90 until it bears on the upper end of stop pin, and the continued downward movement of the lever compresses the spring under the plunger and which operates to hold the stop pin with a yielding pressure against the 95 lower piston 18^a and the needle valve carried by the latter and absolutely prevents any accidental movement or displacement of the needle and consequent flooding of the suction tube 1 of the carburetor. When the 100 throttle valve is closed the needle valve is also closed and is so held by the stop pin until the throttle valve is again opened.

As previously explained the shaft 8 which is a part of the connection between the 105 throttle valve and the upper piston, is mounted eccentrically in the bushing 9 which is connected by crank 13 and rod 14 to operating mechanism located within reach of the operator, so that the bushing may be turned 110 for adjusting or changing the position of the shaft 8 with relation to the upper piston, hence if after the parts have been set it should be found necessary to increase or decrease the amount of fuel to the air admitted around the throttle, this can be accomplished by turning the bushing 9 to elevate the shaft 8 in the event more fuel is needed, or turning the bushing in a direction to lower the shaft and thus decrease the 115 lift of the needle valve in the event less fuel is needed.

With this improvement the action of the needle valve is automatically controlled by the movements of the throttle valve, when 120 the engine is running, but when the engine is not running, and consequently no suction in tube 1, the needle valve will be seated and remain seated until the engine is started.

It is evident that many slight changes 125

might be resorted to in the relative arrangement of parts shown and described without departing from the spirit and scope of my invention. Hence I would have it understood that I do not wish to confine myself to the exact construction and arrangement of parts shown and described but,

Having fully described my invention what I claim as new and desire to secure by Letters-Patent, is:—

1. In a carbureter, the combination of a suction tube having a spray nozzle therein, a cylinder, two pistons in the latter one being free and the other manually adjustable whereby the extent of movement of the free piston carrying the valve is regulated, the suction tube having communication with the cylinder intermediate the two pistons, and a needle valve carried by the free piston and coöperating with the spray nozzle in the suction pipe.

2. In a carbureter, the combination of a suction tube having a spray nozzle and a throttle valve therein, a cylinder, two pistons in the latter one of said pistons having connection with the throttle valve so as to move therewith and the other being free whereby the extent of movement of the free piston is controlled by the extent of movement of the other piston, the suction tube having communication with the cylinder intermediate the two pistons whereby the free piston is lifted by the suction in the suction tube, and a needle valve carried by the free piston and coöperating with the spray nozzle in the suction tube.

3. In a carbureter, the combination of a suction tube having a spray nozzle and a throttle valve therein, a cylinder in communication with said suction tube, a piston in said cylinder and adapted to be moved by the vacuum created in the cylinder, a needle valve carried by said piston and coöperating with the spray nozzle in the suction tube, a stop within the cylinder, means connecting the stop and throttle valve whereby when the throttle valve is opened for the passage of air the stop will be raised to permit the piston carrying the needle valve to rise, and other means for adjusting the stop independently of the throttle valve.

4. In a carbureter the combination of a suction tube having a spray nozzle and a throttle valve therein, a cylinder having communication with said suction tube, a piston in said cylinder and operated by the suction therein, a needle valve carried by said piston and coöperating with the spray nozzle, a stop within the cylinder for limiting the movement of the piston, means connecting said stop and the throttle valve whereby they will be simultaneously adjusted, and means for yieldingly holding said valve on its seat when the throttle valve is closed.

5. In a carbureter, the combination of a suction tube having a spray nozzle and a throttle valve therein, a cylinder having a port communicating with said suction tube, a piston in said cylinder, a needle valve carried by said piston, a stop in the cylinder for limiting the movement of the piston, a cylindrical bushing, a shaft eccentrically mounted in said bushing, means connecting said shaft with the stop, means connecting it with the throttle valve whereby it will have a turning movement simultaneously with that of the throttle valve and means for turning the bushing whereby the relative adjustment of the shaft and throttle valve will be changed.

6. In a carbureter, the combination of a suction tube having a spray nozzle and throttle valve therein, a cylinder having a port communicating with said suction tube, two pistons in said cylinder and at opposite sides of the port, the lower piston being free and adapted to be moved upwardly by suction, a needle valve carried by the free piston, a rotary shaft having a crank connection with the other piston, and connection between said shaft and throttle valve whereby they are actuated in unison for regulating the extent of upward movement of the free piston.

7. In a carbureter, the combination of a suction tube having a spray nozzle and a throttle valve therein, a cylinder having a port communicating with said suction tube, two pistons in said cylinder, one of said pistons being free, a needle valve carried by the free piston, a rotary shaft having crank connection with the other piston, a bushing in which said shaft is eccentrically mounted, means for turning the bushing and means connecting the shaft and throttle valve whereby when the throttle valve is actuated the shaft and the piston connected with said shaft will be actuated to move the said piston away from or toward the free piston.

8. In a carbureter, the combination of a suction tube having a spray nozzle and the throttle valve therein, a cylinder having a port connection with the suction tube, a piston in said cylinder and adapted to be moved upwardly by suction in the cylinder, a needle valve carried by said piston, a movable stop for limiting the opening movement of the needle valve, means connecting said stop and the throttle valve whereby the stop will be moved away from the needle valve when the throttle valve is opened and moved toward the said needle valve when the throttle valve is opened and spring actuated means for holding said stop down on the piston when the suction is discontinued whereby the needle valve will be held down on the spray nozzle and close the latter.

9. In a carbureter, the combination of a suction tube having a spray nozzle therein, a cylinder having a port connection with said tube, two pistons in said cylinder, manually operated means for moving one piston, a needle valve carried by the other piston, a stop carried by the manually operated piston and movable thereby and also having movement independent thereof, a spring actuated plunger, and a lever connected with said manually operated piston and adapted to engage the spring plunger when the manually operated piston is depressed and be forced by the latter into contact with

the adjacent end of the stop, for yieldingly holding the latter down into a position to prevent any accidental opening movement of the needle valve while the manually operated piston is maintained in its depressed position. 16

20
In testimony whereof, I have signed this specification in the presence of two subscribing witnesses.
